UNITED STATES PATENT OFFICE

RASMUS M. HVID, OF CHICAGO, ILLINOIS

REFRIGERATING MACHINE

Application filed October 25, 1927, Serial No. 228,511. Renewed January 6, 1930.

My invention relates to refrigerating devices and particularly to an improvement in a detail of construction of the machine disclosed in my copending application, Serial 5 No. 228,510 filed of even date herewith.

An object of the construction here disclosed is to provide for economical construction and simple and effective assembly of the parts thereof.

10 In order to enable the use so far as possible, of castings in the construction of the principal parts of an ice machine, I have designed a casing construction composed of three parts which may be cast in the proper shape 15 and machined to provide abutting tongue-and-groove fluid-tight joints. Inasmuch as these parts are intended to contain the high pressure gas, the construction should be such that gas leakage throughout the expected 20 life of the device is certainly avoided. To that end, I provide a construction composed of three parts, adapted to be pulled into tight engagement by a plurality of bolts and when so positioned, to be fluid tight thereafter.

25 Another object of the invention is to include simple means for mounting the motor supporting frame on the casing, such means providing for removal and replacement of the motor without interfering in any manner with the remainder of the assembly.

The invention will be more readily understood by reference to the accompanying drawings, in which:

Fig. 1 is a vertical sectional view through 35 a casing construction for ice machines, arranged in accordance with my invention; and

Fig. 2 is a sectional view on the line 2—2 of Fig. 1.

In the drawings I have illustrated the important features of the invention, eliminating 40 details that are not herein claimed. It will be observed that the parts comprising the high pressure chambers include an upper, hemispherical casting, 10, a lower hemispherical casting, 11, and an intermediate horizontally disposed casting, 12. The top wall 13 of the upper casing member 10 is generally flat and horizontally disposed, providing a convenient seat for the legs, 14 of a motor frame, not shown. Thus the motor and its

mounting may be readily applied and removed without interfering with the remainder of the assembly.

The method of constructing and joining all three casing parts, 10, 11, 12 constitutes a 55 distinct advance in this art. The desired result is secured by providing the intermediate member with an annular flange 15, the edge of which registers with an annular groove in the casing member 10. A second 60 groove, 17 having a tapered floor, is provided at the periphery of the horizontal member. The lower casing member 11 has an annular tongue 18 registering with the groove 17 and fitting nicely within the walls of the 65 member 10. Lead or other metal gaskets are inserted in the respective grooves and a force applied through the ears 19, 20, and bolt, 21, tends to pull the parts toward each other. Due to the shape of the groove 17, the clamping 70 force tends to seal all three of the contacting parts. By providing a relatively large number of clamping bolts, as shown in Fig. 2, I am able to secure a high degree of clamping pressure which, when evenly applied, results in a permanent seal between 75 the parts. This is essential in ice machine construction, inasmuch as the chamber is intended to contain high pressure refrigerating gas. The chambers 22, 23, contain 80 high pressure gas, whereas the chamber 24 is low pressure and an efficient seal must be provided therebetween.

Another important point is that by the design here disclosed, I am able to employ metal 85 castings instead of metal stampings, with greatly reduced cost and without a substantial increase in weight.

Various modifications may be made in the design and construction herein illustrated 90 within the skill of the mechanic, and I do not wish to be limited except as indicated in the appended claims.

I claim:

1. In an ice machine, the combination of 95 upper and lower casing members, each of generally hemispherical shape, and a separate intermediate wall, said upper and lower members having angularly spaced ears, said three parts having abutting, cooperating grooves 100

and flanges, gaskets between the abutting portions, and bolts engaging the respective lugs and adapted to pull the three parts into gas-tight abutting relation.

- 5 2. In combination, upper and lower casing members and a separate, intermediate wall member having an annular flange and an annular groove, the upper member having the annular groove adapted to cooperate with the
10 flange on the intermediate member, and the lower member cooperating with the groove in said intermediate member, lugs on said upper and lower members, and bolts engaging the lugs and adapted to pull the upper and lower members toward each other and to join the
15 respective flanges and grooves of the three parts to provide a fluid tight connection.
3. In combination, upper and lower casing members of generally hemispherical form
20 and an intermediate member serving to divide the space within said first members into two chambers, said three members being composed of cast material, said three members having cooperating flanges and grooves, apertured lugs on said upper and lower members, and bolts engaging the lugs and adapted to
25 pull the parts together to form a fluid tight connection between the three parts.

4. In an ice machine, the combination of
30 upper and lower members providing a high pressure chamber, a wall dividing said chambers, said intermediate wall having an annular flange and a peripheral groove, said upper member having an annular groove for engagement by the annular flange, and said lower member having its marginal portion shaped to engage the annular groove in said intermediate wall, and means engaging the upper and lower members and adapted to
35 pull the same together and to confine the intermediate wall in gas-tight relation thereto.

In testimony whereof I have affixed my signature.

RASMUS M. HVID.
